COMBINATION MILL AND UNDER-REAMER
FOR OIL WELLS

Robert E. Clark, Jr., Houston, Tex.

Application November 27, 1950, Serial No. 197,695

5 Claims. (Cl. 255—76)

1

This invention relates to a combination cutting, milling, and under-reaming tool for wells, as oil wells, such tool being adapted to be installed on the end of a tubing string, as the rotary drill string, to first cut through the casing of the cased well bore, and then to mill a window in the casing as the under-reamer is extended to under-ream the formation outwardly of the window.

It is an object of this invention to provide a combination cutting, milling and under-reaming tool adapted to be installed on the end of a tubular string, as the drill string in a well bore, to cut through and then mill a window through the well bore casing and to under-ream the formation outwardly of the window.

It is a further object of this invention to apply pressure to fluid in the tubular string above the tool to operate on a means to extend both the milling cutters and under-reamers of the tool and at the same time to supply the fluid to lubricate the operation of such cutters and under-reamers.

It is a further object of this invention to provide a low pressure area within the bottom of the tool into which the cutter and under-reamer operating means or plunger extends, so that there is a pressure differential between the upper portion of the operating means or plunger, and the lower portion thereof, thereby insuring that the plunger moves downwardly to positively extend the cutter and under-reaming means.

It is yet a further object of this invention to provide a tool of this class having a low pressure area in the base thereof which is punctured when the window is milled and when the under-reamer is at full extension.

It is yet another object of this invention to provide a tool of this class having a low pressure area punctured at the point of lowest plunger travel to indicate the end of the milling and under-reaming operation by a pressure drop indicated at the top of the well.

It is yet another object of this invention to provide a tool of this class which is adapted to have pressure fluid washed through the base thereof when the low pressure area therein is punctured at the end of the milling and under-reaming operation.

Other and further objects will be apparent when the specification is considered in connection with the drawings in which:

Fig. 1 is a sectional elevation prior to the insertion of the operating plunger.

Fig. 2 is a sectional elevation prior to the in-

2

sertion of the operating plunger, such elevation being taken at 90° from that of Fig. 1.

Fig. 3 is a sectional plan view taken along line 3—3 of Fig. 1.

Fig. 4 is a sectional plan view taken along line 4—4 of Fig. 1.

Fig. 5 is a sectional plan view taken along line 5—5 of Fig. 1.

Figs. 6 is a sectional plan view taken along line 6—6 of Fig. 1.

Fig. 7 is a sectional plan view taken along line 7—7 of Fig. 2.

Fig. 8 is a sectional elevation, similar to the section shown in Fig. 1 and showing the under-reamers in the process of being extended to under-ream.

Fig. 9 is a sectional elevation, similar to the sectional elevation shown in Fig. 2, showing the milling cutters in the process of cutting into the casing.

Fig. 10 is a sectional elevation similar to the elevation shown in Fig. 1 which shows the under-reamers fully extended.

Fig. 11 is a sectional elevation similar to the sectional elevation shown in Fig. 2 which shows the milling cutters fully extended after a window has been cut.

Fig. 12 is a sectional elevation of the bottom of the well in which the casing terminates.

In Fig. 1 a tubular string, as a drill string 1, extends from the top of the well into the well bore 2 which is enclosed by the casing 3. A tool body 4 is adapted, as by the thread engagement 5, for connection to the drill string 1. The head 6 of the body 4 is recessed at the top to receive therein the bumper 7 which is made of a resilient material to fit within the bore 8 of the body. The bore 8 extends downwardly and communicates at 9 with the openings 10 and 11. These openings have pins or axles 12 extending thereacross and under-reamers 14 are pivotally mounted thereon. These under-reamers have straight outer faces 15, as shown in Fig. 1, and bevelled inner faces 16 to serve as cam surfaces.

In order to cut the formation to be under-reamed, the under-reamers 14 have hardened cutting surfaces provided, as the diamonds 17. Below the under-reamers in the openings 10 and 11 are pivotally mounted, as on the pins 18, the cam arms 19, which have the cam rollers 20 pivotally mounted on the pins 21 thereof.

As shown in Fig. 3, the passages 23 and 24 are provided to extend tangentially outwardly from the bore 8. The bushings 25 are provided to be inserted in the enlarged inner portions 23' and

50 55

24' of the passages 23 and 24 respectively, to limit the orifices provided to various required sizes.

As shown in Figs. 1 and 2 below the passages 23 and 24 are provided the passages 27 and 28 which extend diagonally downwardly from the bore 3 into the openings 29 and 30 to direct fluid, as drilling mud, onto the cutting edges 31 and 32, respectively, of the milling cutters 33 and 34 respectively. These milling cutters are pivotally mounted on the pins or axles 35 which extend across the openings 29 and 30. The cutting edges 31 and 32 are tempered or surfaced with a hardened material as diamonds.

Before the tool 4, at the end of a drill string 1, is lowered into the well, shear pins 37 are inserted through the under-reamers 14 and into the body on either side thereof to hold these elements in position, and retracted from any possible contact with the casing wall 3. Shear pins 36 also are provided to hold the milling cutters 33 and 34 out of contact with the casing wall 3.

When the drill string 1 has been lowered to position the tool 4 at a desired elevation in the well, as an elevation adjacent an oil producing sand, the plunger 40 is dropped from the top of the well down the bore 41 of the drill string. This plunger 40 will seat upon the bumper 7 and will be restrained at this position until a force is applied from above to force the plunger downwardly. This force is supplied by filling the bore 41 of the drill string 1 with a fluid, as drilling mud, and by applying a force at the top of the well, as the power of a pump, to exert a pressure upon the top surface 43 of the plunger 40. After the plunger has passed through the bumper 7 the outer surface 44 thereof is in contact with the O-ring seal 45 to restrain the fluid from passing further downwardly.

To maintain a balance to accommodate any pressure built up in the drill string bore 41, in excess of that pressure required to move the plunger 40 downwardly, the passages 23 and 24 operate on the dashpot principle to by-pass part of the delivered fluid out into the annular space 55 between the drill string 1 and the casing 3.

As the fluid forces the plunger downwardly it first contacts the inner corners 46 of the milling cutters 33 and 34 to begin moving them outwardly. At this point it should be noticed that the shear pins 36 have been severed at the beginning of outward movement of the milling cutters. As this is done the O-ring seal 45 is in contact with the outer plunger surface 44, but the passages 27 and 28 are being uncovered. This increases the outflow of fluid into the annulus 55, under the dash-pot principle, and at the same time supplies drilling mud through the passages 27 and 28 to lubricate the milling cutters.

In case it may be desired to limit the flow of fluid through the openings 27 and 28, the bushings 49 and 50 may be installed therein as shown in Figs. 2, 9, and 11, thereby restricting the flow passage through such opening. Such bushings, of various inner diameters, may be provided to control the various volumetric flow requirements which it may be necessary to obtain for satisfactory operation.

When the plunger 40 first contacts the milling cutters, they are moved outwardly from the position shown in Fig. 2 to contact the wall of the casing 3. As the drill string 1 is rotated the milling cutters begin to cut a groove in the casing wall, and continued rotation, as the fluid pressure forces the plunger further downwardly, increases

the depths of this groove until the casing wall is finally cut through and severed. After this is accomplished, the drill string 1 is lowered as it is rotated and the milling cutters, fully extended by the downward movement of the plunger, as shown in Fig. 9, mill a window in the well bore or rather enlarge the width of the severance of the casing 3.

While the plunger surface 44 is in contact with the milling cutter corners 46 to extend them to cut through the casing wall 3, the seating surface 75 of the plunger and the plunger parts therebelow are adjacent to, and are passing by the under-reamers 14 in spaced relation therefrom.

After the plunger 40, in its downward passage responsive to fluid pressure, has contacted the milling cutters 33 and 34 and the window described hereinabove has been cut, it further contacts the rollers 20 of the cam arms 19 to force these arms against the under or inner sides 16 of the under-reamers to force them outwardly into the window made by the milling cutters, as best shown in Fig. 8. The initial contact severs the shear pins 37 to permit this outward movement of the under-reamers.

The rotation of the drill string 1 then rotates the under-reamers against the formation outwardly of the casing 3 to under-ream or enlarge an area outwardly of the window while the milling cutter continues to enlarge the window as shown in Fig. 11 when this figure is considered in relation to Fig. 10. This enlargement is made for the purpose of exposing producing veins or crevices through which fluid, as oil, may flow into the annular space 55 between the casing 3 and drill string 1.

As shown in Fig. 12, prior to the beginning of the milling and under-reaming operation, the casing 3 has been cemented at the bottom 61 and cement has been forced upwardly there-around in the annular space 56 into which the casing has been originally inserted. This cement extends substantially above the place where the window is to be cut and approximately to the top of the well. When the window 57 has been cut and an area 58 of concrete removed outwardly thereof by the milling cutters, the fluid which flows from the formation 59 enters the under-reamed space 60 and fills the space below the drill string 1 and tool 4 to the cemented bottom 61 of the casing 3. The fluid, as oil, then must naturally rise upwardly in the casing 3 above the tool 4 and around the drill string 1.

When the lower portion or end 65 of the tool 4 is considered, the O-ring seal 66, the diaphragm 67, the chamber 68, and the retaining ring 69, and the diaphragm 70 are pointed out as the means which prevents a substantial pressure to oppose a downward motion of the plunger 40.

When the spear end 71, of the plunger 40, having the point 72 thereon, moves through the seal 66, a limited further travel causes it to puncture the diaphragm 67 to enter the chamber 68. This chamber 68 is originally sealed at atmospheric pressure so that at the time of puncturing the diaphragm 67, the spear end 71 moves into a low pressure area as compared with the area above the seal 66, the contact of the spear end periphery 73 serving at this time, by this contact with the O-ring seal 66, to maintain this differential. This differential is necessary as otherwise the downward motion of the plunger would be opposed by a pressure equal to that in the fluid thereabove with the result of effective

opposition to the downward travel of the plunger.

After the spear end 71 punctures the diaphragm 67 it continues to move further downwardly until it finally comes in contact with the diaphragm 70. This occurs at the point when the under-reamers 14 are fully extended. At this time the milling cutters 33 and 34 have been milling away in cutting the window in the casing 3 as the drill string has been both lowered and rotated. Finally, the last downward movement of the plunger 40 forces the spear point 72 of the spear end through the diaphragm 70 and at the same time the spear surface 73 breaks contacts with the O-ring seal 66. Also, the conical seating surface 75 of the plunger 40 seats on the ribs 76 which are radially spaced about the countersunk bore 77. Furthermore the plunger 40 moves out of surface contact with the O-ring seal 45.

When the plunger is at its lowest point of travel and is seated on the ribs 76, fluid, as drilling mud, can wash downwardly through the tool 4 and through the openings between ribs 76 and will pass through the chamber 68 and around the spear end 71 and flow out the broken diaphragm 70. This free circulation of fluid which follows the puncturing of the diaphragm 70 and the equalizing of pressure within the well, is a desirable feature at this stage of operation as it is preferable, especially with under-reaming at completion, to wash through the tool and to circulate fluid fully to clean the under-reamed spaces.

This invention combines in one structure the equipment required to cut through the casing wall and mill a window in the casing, with the equipment conventionally used separately to under-ream an area around the opened casing. Heretofore, it has been necessary to make one trip into the well with the milling cutter means installed on the drill string, then remove the drill string and follow by making another trip in the well with the under-reaming means installed on the drill string. Additionally, conventional means have not employed pressure of a fluid, as drilling mud in most cases, to operate either the milling cutter means or the under-reaming means.

It can be seen that an invention of this type saves at least one trip into the well for each window which has to be cut. The employment of such an invention also results in a considerable cost saving over devices which require some mechanical means at the top of the well to operate the milling cutter or the under-reamer in addition to the rotating force applied to the drill string.

It is particularly pointed out that the form of invention disclosed is not the only structure capable of carrying out the function and theory of this invention. The chamber 68, sealed at atmospheric pressure, might be eliminated and the bottom of the tool may consist of an opening of considerable size. Such a construction is recommended where deposits of sand might settle within the tool to interfere with its operation, particularly with the retraction of the plunger 40. In such modification as may be employed to avoid this occurrence the vertical spacing between the ports 23 and 27 should bear such a relation to the shape and dimensions of the plunger that a sequence of occurrences as follows may take place.

First, there will be a pressure drop when the top portion of the plunger surface 44 begins

clearing the ports 23. Such beginning of clearance takes place at a time when the milling cutters 33 and 34 have cut through the casing 3. Then, by the time the plunger begins operating to extend the under-reamers 14 the top portion of the plunger surface 44 begins to uncover the passages 27 and 28 to permit fluid to lubricate the milling cutters 33, 34. The uncovering of the passages 27 and 28 is naturally accompanied by a second pressure drop indicated at the top of the well. In such a modification, the passages 27 and 28 may have an opening through the bore 8 of considerable vertical length and width and therefore the maximum pressure drop which will be indicated at the top of the well will occur at maximum extension of the under-reamers.

The structures are also even included within the concept of this invention which may operate the milling cutters to full extension first and then 20 the under-reamers thereafter in sequence. This can be accomplished simply by providing a longer plunger and a longer body with the under-reamer cams spaced in the body a distance below the milling cutters so that the plunger will not begin 25 extending the under-reamers into the window until the milling cutters are at full extension.

It is obvious that the plunger 15, by the shape 30 of its head, is engageable by any of the many conventional type of grapples or retrieving tools now employed in oil well practice. Such a device is lowered on a wire line until it strikes upon, and is guided over the plunger head by virtue of its shape and the shape of the plunger head, and by the pull of gravity on the weight of the 35 retrieving tool. Such tool has locking parts urged yieldably inwardly which lock under the head of the plunger so that the plunger may be withdrawn from the tool body 2. Then it is obvious that, when the drill string 1 is raised, 40 the milling cutters and under-reamers will pivot inwardly and swing by gravity within the tool body 2.

Broadly, this invention considers a method and 45 structure of providing a tool including both milling cutters and under-reamers therein, such tool being installed on a drill stem or operating string and positioned in the well at a desired level. The invention then considers operating the tool at such level by force, as by fluid pumped from the top of the well, so that a window may be made 50 in the casing and an annular space underreamed outwardly of the window to expose a greater surface area of producing formation to the flow of fluid as oil, such results being obtainable by one trip into the well of the tool and 55 operating string.

What is claimed is:

1. With a rotary tubular string in a cased well bore adapted to have fluid under pressure supplied thereto from the top of the well, the combination of, a tubular tool body having recess means therein and adapted for connection to the body of said string, milling cutter means and underreamer means each separately pivotally mounted in said recess means in vertically spaced apart relation, a plunger in said body and operable responsive to said fluid pressure to successively engage the cutter means and the underreamer means and to first extend said milling 60 cutters to cut through and then to mill a window in said casing after the cutter means has been fully extended and to extend said underreamer means through said window to underream the formation outwardly of the casing as said window is being milled.

2. With a rotary tubular string in a cased well bore adapted to have fluid under pressure supplied thereto from the top of the well, the combination of, a tubular tool body having recess means therein and adapted for connection to the body of said string, milling cutter means and underreamer means each separately pivotally mounted one above the other in said recess means, a plunger in said body having a camming formation thereon, means to project said plunger in steps to swing said cutter and underreamer about their pivots by successive camming formation engagement therewith, first to extend said milling cutters to cut a window in said casing, and after extension of the cutter to extend said underreamer means through said window to underream the formation outwardly of the casing.

3. With a rotary tubular string in a cased well bore adapted to have fluid under pressure supplied thereto from the top of the well, the combination of, a tubular tool body having recess means therein and adapted for connection to the body of said string, milling cutter means and underreamer means spaced vertically one above the other and each separately pivotally mounted in said recess means for projection from a retracted position, a plunger in said body and operable responsive to said fluid pressure to first project said milling cutters to cut a window in said casing, and to thereafter project said underreamer means through said window to underream the formation outwardly of the casing, a frangible diaphragm and a seal in said body below said recess means and a closure in said body therebelow so that said diaphragm and said closure enclose a space in said body at substantially atmospheric pressure, said diaphragm being puncturable by the weight of said plunger and said seal sealing around the plunger to enclose the lower end of said plunger in said space.

4. With a rotary tubular string in a cased well bore adapted to have fluid under pressure supplied thereto from the top of the well, the combination of, a tubular tool body having a continuous axial passage therethrough and lateral recess means therein and adapted for connection to the body of said string, milling cutter means and underreamer means each separately pivotally mounted in said recess means one above the other, and means operable responsive to said fluid pressure to first swing said milling cutters to outwardly projected position to cut through and then to mill a window in said casing, and thereafter to swing said underreamer means

through said window to underream the formation outwardly of the casing as said window is being milled, said tool providing a seat for said cutter and underreamer extending means at the end of underream extension, said seat being adapted to permit the continued flow of fluid through said passage.

5. With a rotary tubular string in a cased well bore adapted to have fluid under pressure supplied thereto from the top of the well, the combination of, a tubular tool body having recess means therein and adapted for connection to the body of said string, milling cutter means and underreamer means in vertically spaced apart relation and each separately, pivotally mounted in said recess means for movement from a retracted to an extended position, a plunger in said body operable responsive to said fluid pressure and engageable, first, with said milling cutter means to project the same into cutting relation with said casing to cut a window therein and thereafter to project said underreamer means through the window to underream the formation outwardly of the casing, a frangible diaphragm and a seal in said body below said recess means, a closure in said body therebelow so that said diaphragm and said closure enclose a space in said body at substantially atmospheric pressure, said diaphragm being puncturable by the weight of said plunger and said seal sealing around the plunger to enclose the lower end of said plunger in said space, said plunger having a seal by-pass portion in inoperative position above said seal while milling and underreaming and the pressure of said fluid forcing said plunger downwardly to puncture said closure and bring the by-pass portion into operative position below said seal as milling and underreaming are concluded whereby said fluid may wash axially through said tool.
